(57) **CLAIM**

The ornamental design for a roof for utility vehicles, as shown and described.

DESCRIPTION

FIG. 1 is a front elevational view of a roof for utility vehicles showing my new design;

FIG. 2 is a rear elevational view thereof;

FIG. 3 is a left side elevational view thereof, the right side view being a mirror image of that shown;

FIG. 4 is a top plan view thereof;

FIG. 5 is a bottom plan view thereof;

FIG. 6 is an upper front perspective view thereof; and,

FIG. 7 is a lower front perspective view thereof.

The subject roof is installed in a utility vehicle at the upper portion.
